UNITED STATES PATENT OFFICE.

JOHN C. HEDGES, OF DES MOINES, IOWA.

LOOSE-LEAF BINDER.

1,138,104.

Specification of Letters Patent.

Patented May 4, 1915.

Application filed March 24, 1913. Serial No. 756,608.

To all whom it may concern:

Be it known that I, JOHN C. HEDGES, a citizen of the United States, residing at Des Moines, in the county of Polk and State of Iowa, have invented a certain new and useful Loose-Leaf Binder, of which the following is a specification.

The object of my invention is to provide a binder for loose leaves or for loose leaf books of simple, durable and inexpensive construction.

A further object is to provide a binder employing a sleeve and screw correspondingly screw threaded and provided with simple means for locking them in any of their relative positions.

My invention consists in certain details, in the construction, arrangement and combination of the various parts of the device, whereby the objects contemplated are attained, as hereinafter more fully set forth, pointed out in my claims and illustrated in the accompanying drawings, in which:

Figure 1 shows an end elevation of a loose leaf book binder embodying my invention, the dotted lines showing the device in its fully extended position. Fig. 2 shows a longitudinal, vertical, sectional view through my improved book binding device. Fig. 3 shows an inverted plan view of a portion of one side of my device. Figs. 4 and 5 show detail, sectional views of portions of the mechanism. Fig. 6 shows a detail view of the outer end of one of the screw heads, part of said head being broken away. Fig. 7 shows an end elevation of a modified form of my book binder. Fig. 8 shows a top or plan view of said modified form. Fig. 9 shows a longitudinal, vertical sectional view through a portion of the modified form of my improved binder. Fig. 10 shows a sectional, detail view illustrating the ratchet and spring pawl of the modified form, and Fig. 11 shows a detailed view of a part of the preferred form of the binder.

In the form of my device shown in Figs. 1 to 6 inclusive, I provide two body members, each comprising a horizontal wall 10 and a vertical wall 11. In this description, I am assuming that the binder is used with a book lying flat, and I am giving the reference numerals applied on the parts on the accompanying drawings. The members 11 rest adjacent to each other, as shown in Fig.

1 and are designed to slide vertically with 55 relation to each other.

Substantially in the middle of my binder from end to end thereof, I provide connecting means preferably constructed as follows: Secured to the member 10 of one of 60 the body members of my binder is a sleeve or cylinder 12 extending toward the other member 10 parallel with the members 11. Secured to the member 10 of the other body member is a pin or cylinder 13 slidably received within the sleeve 12 and having at its free end an enlarged head 14. The free end of the sleeve 12 is contracted at 15 to limit the telescopic movement of the sleeve 12 and the member 13 with relation to each 70 other. Between the head 14 and the adjacent member 10 is an expandable coil spring 16 designed to yieldingly hold the sleeve 12 and the pin 13 at the outward or extended limit of these movements with relation to 75 each other.

Secured to one of the members 10 is a part of an adjustable fastening device which I shall now describe: I preferably employ two adjustable fastening devices, one of 80 them being near each end of the binder. These devices are of similar construction and I shall therefore describe but one of them. I provide a flat bar twisted to form a screw threaded portion 17 and having at 85 one end a portion 18 bent at right angles to the portion 17. The portion 18 is not twisted. The portion 18 may be secured to the outside of the portion 10 by means of a rivet 19 and is extended through an opening 20 90 in the portion 10 near the free edge thereof. The twisted portion 17 is extended toward the opposite portion 10 and is arranged parallel with the sleeve 12.

Mounted upon the portion 17, I preferably provide a sleeve 21 having at its end adjacent to the portion 10 and around the opening 20 an annular flange 22. I provide a plate 23 designed to be secured to the wall of the part 10 and provided with a central 100 opening to receive the sleeve 21 and provided with a central raised portion to receive the flange 22, and having a portion 24 folded or bent over the free edge of the portion 10. The plate 23 is secured to the portion 10 by 105 said rivet 19. Slidably and rotatably mounted in the other wall or portion 10, I provide a cylinder 25 which telescopically

receives the portion 17 and is provided in its wall with screw threads 26 which coact with the screw threads formed by twisting the portion 17. The cylinder 25 is received within the sleeve 21.

On the outer end of the cylinder 25 outside the body portions of the binder is a head 28 having a slot 29 to receive a screw driver. The under or inner side of the head 28 is provided with a plurality of notches 30, designed to engage and coact with lugs or portions 31 which may be made by punching small holes in the portion 10 around the cylinder 25 and pressing the parts 31 outwardly. The edges of the leaves of a book 32 are placed between the portions 10 of my binder and are provided with holes to receive the sleeves 12 and 21 and the cylinders 25 and 13.

In the practical use of my improved binder, I preferably use the binder with leaves having slots to receive the members 12 and 13 for the reason that I preferably use the member 12 with the bracket end 15 which prevents the complete separation of the main body members of my binder.

It will readily be seen that the spring 16 normally holds the body members apart from each other. By pressing the members 30 toward each other at either end, the lugs 31 may be moved away from the notches 30 and the cylinder 25 may be unscrewed and if desired withdrawn entirely from the binder. New leaves can then be slipped over the members 12 and 13 and the member 25 may be replaced after the leaves have been placed over the cylinders 21. As long as the spring 16 operates the binder will be held locked by means of the lugs 31 and the notches 30.

In Figs. 7 to 10 inclusive, I have shown a modified form of my device especially designed as a loose leaf binder where no back members are used. In the form of the device shown in Figs. 7 to 10, I have provided 45 one body member comprised of a channel which may be, if desired, substantially rectangular in cross section with part of its outer wall cut away. I have indicated the member just described by the reference numeral 35. Extended through the member 25 is a twisted bar 17 having a right angled extension 18 secured to the member 35 by the rivet 19. I preferably provide members 17 near each end of the member 35. The member 35 is designed to rest against the leaf mounted on, or a book mounted on the members 17.

I provide another body member of the modified form of my device comprising a horizontal wall 37, the edges of which are turned upwardly to form vertical walls 38. The upper edges of the walls 38 are turned toward each other to form short horizontal walls 39. In the walls 39 I cut a plurality of slots 40 and press a small part of the

material downwardly forming engaging devices 41. The wall or plate 42 has its edges received between the walls 39 and the engaging devices 41 on each side of the body member now being described. Other forms of body members may be used, the essential features being to provide a body member substantially rectangular in cross section which may be easily assembled.

Rotatably mounted in the plate 42 in line 75 with the members 17 are cylinders 43 which extend outwardly away from the binding device. On the inner ends of the cylinders 43 between the plate 42 and the wall 37 are ratchet wheels 44 mounted on the cylinders 80 43. The walls of the cylinders 43 are provided with screw threads or screw threaded indentations 45. The cylinders 43 are designed to receive the twisted bars 17 and the screw threads 45 are designed to coact with 85 said twisted bars.

It will readily be seen that by locking the ratchet wheel 44, the members 17 and 43 may be locked with relation to each other. For locking the ratchet wheels 44 in any 90 position of their movement, I provide springs between the wall 37 and the plate 42 which may be described as follows: I provide a spring having a member 46 designed to engage one of the walls 38, a transverse member 47 and an inclined member 48 designed to engage the other wall 38. The form of said spring may be varied as desired; it being my purpose to provide a spring which will be held frictionally 100 between the walls 38.

Formed on the member 46 is an extension 49 designed in one position of the sliding movement of said spring to engage the teeth of the ratchet wheel 44. The extension 49 105 extends through a slot 50 in the plate 42 to position where it is readily accessible from outside the binder.

In the practical use of the modified form of my binder, the members 17 are extended 110 through holes 50 in the leaves of a book. The cylinders 43 are dropped over the members 17 and the wall 37 may be pressed toward the member 35 and when the leaves of the book are pressed tightly together the 115 binder may be locked by pushing the extension 49 into engagement with the ratchet wheel 44.

My improved book binder has a great many advantages, many of which are obvious from the foregoing description. The device is of comparatively simple and inexpensive construction. For the screw threaded members 17 I provide twisted bars and for the members 43 and 25, I provide 125 ordinary thin walled cylinders into which screw threads may be readily pressed.

It will be readily seen that a great many variations may be made in the details of the construction of my device and it is my in- 130

tention to cover any variation of construction which may be included within the scope of the appended claims.

I claim as my invention:

- 5 1. In a device of the class described, a binder member designed to engage one side of a book, externally screw threaded devices carried by said binder member and designed to be received in holes in the leaves
- 10 of a book comprising a twisted bar extending through said binder member and provided with a right angled extension secured to the surface thereof, a second binder member designed to engage the other side of the book, a plurality of hollow cylinders mounted thereon, each of said cylinders having screw threads formed in its walls and being designed to receive one of said first named screw threaded members, and means for locking said cylinders and screw threaded members in various positions of their movement with relation to each other.
- 15 2. In a device of the class described, spaced

binder members, a screw threaded engaging device mounted on one binder member, a 25 coaxing screw threaded engaging device rotatably and slidably mounted in the other binder member yielding means for holding said binder members apart, a head on the second engaging device outside the binder 30 member in which it is mounted, said last named member and said head being formed with portions adapted to coact and prevent rotation of the second engaging device when the binder members are at the limit of their 35 movement, away from each other and to become inoperative and to permit rotation of the second engaging device when the last described binder member is moved toward the other binder member slidably on the 40 second engaging member.

Des Moines, Iowa, March 5, 1913.

JOHN C. HEDGES.
